UNITED STATES PATENT OFFICE.

SAMUEL D. PALMER, OF ROCKFORD, ILLINOIS.

CHURN.

SPECIFICATION forming part of Letters Patent No. 541,945, dated July 2, 1895.

Application filed September 8, 1894. Serial No. 522,429. (No model.)

To all whom it may concern:

Be it known that I, SAMUEL D. PALMER, a citizen of the United States, residing at Rockford, in the county of Winnebago and State 5 of Illinois, have invented certain new and useful Improvements in Metallic Churns, of which the following is a specification.

The object of this invention is to construct a churn body, in two sections, a ring of angle 10 iron in connection with one section forming a receptacle to receive a packing, and a fastening supported by one section for uniting the sections consisting of a pair of bails, each bail supporting a cam which engages the 15 other section.

In the accompanying drawings, Figure 1 is an elevation of a churn, showing my improvements. Fig. 2 is an elevation of the churn as seen when looking against one of the trunnions. Fig. 3 is an isometrical representation of the angle iron ring. Fig. 4 is an enlarged vertical section of a section of the churn body and of the angle iron ring. Fig. 5 is a vertical section of the upper portion of 25 the top section of the churn body. Fig. 6 is an isometrical representation of the movable rest for the cam.

The lower section 1 of the churn body is of dish form, having the material of its open end 30 bent back parallel with its sides and then bent at right angles to the body portion, as shown at Fig. 4.

The upper section 2 is of substantially the same conformation and size as the lower section 35 having an iron ring 3, held by the material of its open end encircling it.

A ring of angle iron consisting of a base 4 and rim 5 has ears 6 made integral therewith, located at four equidistant points, and 40 from the outer face of the rim extend trunnions 7 and 8, the latter having its end fitted to receive a crank. The opening of the base of this ring is sufficient to receive the lower section 1 of the churn body, and receives the 45 outwardly extending flange 9 of the section, and screws 10, passing through the flange enter screw threaded holes 11 in the base, thereby joining the ring to the lower section of the churn body. The annular recess 50 formed by the rim of the angle iron ring, the flange 9, and vertical side of the churn body

are fitted with a packing 12, as shown at Fig. 4, and the open end of the upper section rests upon the packing.

Within the ears 6 are located screw 55 threaded eyebolts 13, and a nut 14 is placed thereon above the ear and a nut 15 below it, and by means of these nuts the bolts can be vertically adjusted and firmly clamped. To a pair of these eye bolts is pivoted a bail 16, 60 and a similar bail 17 is pivoted to the remaining pair of ears, and to each bail is pivoted a cam lever 18.

To the upper section of the churn body near its closed end and to opposite sides of the 65 section, are secured brackets, composed of a base 19, having overturned lips 20, and a section 21, bent to form a socket 22, having its walls perforated. A portion of the base is provided with an elongated opening 23. 70

A plate composed of a base 24 and vertical portion 25 is placed in connection with the bracket secured to the upper section of the churn body, by its vertical portion sliding in a guide way formed by the lips 20, and a projection 26, extending from the upper end of the vertical portion is bent into the elongated opening 23, thereby preventing the displacement of the plate. 75

A nut 27 is placed in the socket of the 80 bracket and a bolt 28 is passed through the opening in the lower wall of the socket, through the nut and through the opening in the upper wall of the socket, and presses against the under face of the plate held by the 85 bracket. The nut is held from turning by the outer end wall of the socket.

The upper section of the churn body is placed in position upon the packing of the lower section. The bails are then moved 90 upon their pivots until the cam levers engage the base of the plates, and a movement of the cam levers will cause the levers to rest upon the plates, thereby forcing the upper section against the packing, forming a water tight 95 joint, and by means of the bolts 28, the pressure applied by the cam lever may be varied by raising or lowering the plates upon which the cam levers rest, or by the adjustment of the eye bolts 13.

The angle iron ring in its connection with the lower section of the churn body forms a 100

support for the section, holding it in proper form, and in connection with the section forms a recess for the packing.

The wedge shaped ring herein referred to is not claimed in this application, but is claimed in an application filed by me August 24, 1894, Serial No. 251,241.

I claim as my invention—

1. In a churn, the combination of a churn body in two sections, one of the sections having the material of its open end bent back upon itself and thence substantially outward therefrom, a ring of angle iron having the horizontal bend of the section secured to the upper face of the horizontal portion of the angle iron, forming a receptacle for a packing, the ring having trunnions extending therefrom.

2. In a churn the combination of a churn body in two sections joined at their open ends, and means for connecting the sections consisting of a pair of bails having a pivotal connection with one of the sections, brackets secured to opposite sides of the other section, an adjustable shelf connected to each bracket,

and a cam pivotally connected to each bail and adapted to engage the shelves.

3. In a churn, the combination of a churn body in two sections joined at their open ends, and means connecting the sections consisting of a pair of bails having a pivotal connection with one of the sections, brackets secured to opposite sides of the other section, nuts held in place by the brackets, a shelf having a slideable engagement with each bracket, a bolt connected to each nut and supporting its shelf, a cam pivotally connected to each bail and engaging its shelf.

4. In a churn, the combination of a body portion in two sections, an angle iron ring supporting one of the sections, eye bolts having a connection with the ring, bails having a pivotal connection with the eye bolts, a cam lever supported by each bail and means connected with the other section for receiving the cam levers, said means made adjustable.

SAMUEL D. PALMER.
